UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

TERRY-LOOM.

1,341,929.

Specification of Letters Patent.

Patented June 1, 1920.

Application filed October 14, 1919. Serial No. 330,541.

To all whom it may concern:

Be it known that I, ALONZO E. RHOADES, of Hopedale, in the county of Worcester and State of Massachusetts, have invented 5 certain new and useful Improvements in Terry-Looms, of which the following is a specification.

The present invention consists in improvements upon the type of terry looms 10 set forth in Letters Patent of the United States of Charles F. Merrill, No. 1,322,715, November 25, 1919. In the loom of that patent the terry or beat-up motion is automatically controlled by a pattern mechanism so that alternating stripes of plain 15 and terry fabric are woven. The pattern mechanism controls a latch which connects the beat-up motion shaft to its actuating cam. When the latch is withdrawn plain 20 weaving is done, and when it makes connection terry weaving ensues. Now, with the mechanism of the aforesaid Merrill patent it occasionally happens, when the latch is released by the action of the pattern mechanism 25 that it fails to connect promptly the beat-up motion shaft with its actuating cam with the result that the terry loops first beaten up are too short thus marring the appearance of the fabric.

30 The object of the present improvements is to insure the immediate connecting action of the latch when called by the pattern mechanism so that the first terry loops woven shall be of full length.

35 The improvements are illustrated in the accompanying drawings, in which—

Figure 1, is a plan view of the connections between the beat-up motion shaft and its actuating cam. Fig. 2, is a section in the 40 plane indicated by the line 2—2 in Fig. 1. Fig. 3, is an enlarged view of certain of the parts. Fig. 4, is a section in the plane indicated by the line 4—4 in Fig. 3. Figs. 5, 6 and 7, are enlarged detail views of the different connecting elements.

The beat-up motion shaft A, is rocked from the cam B, on the continuously rotating shaft C, by the illustrated mechanism. Fast on the shaft A, is a crank arm D, 50 shown in Fig. 1. The cam lever is made in two parts E, and F, shown respectively in Figs. 6 and 7. The part E, will be called the "connector" because it carries the latch G, which connects (under the call of the 55 pattern mechanism) the cam lever to the

crank arm D, and hence to the shaft A. The part F, will be called the "transmitter" because through it the movement of the cam is transmitted to the beat-up motion shaft.

The connector E, is loose on the shaft A, 60 and is maintained in juxtaposition to the crank arm D, by the collar a. The latch G, is pivoted to the connector at b, and is moved to its latching position by a spring H (Fig. 1). The latch is withdrawn by the 65 pattern mechanism as set forth in said Merrill application through connections, of which a link c, lever d, and wire e, are shown in Fig. 2. The latching tooth f, of the latch always occupies a locking slot g, 70 in the connector.

The crank arm D, has a locking notch h, for the reception of the latching end of the latch. When the latch is withdrawn from the notch h, by the pattern mechanism, as 75 shown in Fig. 1, the cam lever is functionally disconnected from the beat-up motion shaft; the cam imparts no motion to said shaft; and plain fabric is woven. When the pattern mechanism releases the latch its 80 latching end enters the slot h, under the impulse of the spring H; the beat-up motion shaft is rocked; and terry fabric is woven.

The crank arm carries a headed stud I 85 (Fig. 1), the shank of which extends through a motion limiting slot J, in the connector. A contractile spring K, is attached at its upper end to an upwardly extending standard i, of the crank arm, and at its 90 lower end to an eye j, on the connector. Accordingly, when the latch is withdrawn from the notch h, the spring K, acts to lift the connector until the bottom of the slot J, seats against the bolt I, thus definitely positioning the connector with respect to the crank arm so that then the slot g and notch 95 h are in register. This is the condition when the latch is released by the pattern mechanism. Consequently, the latch makes sure 100 and prompt connection at the right moment, and the first terry loops beaten up are of full length.

The transmitter F, has a knuckle joint connection with the connector, k, being the 105 joint pivot. The cam C, is an open faced one, and the transmitter cam roll l, is maintained against the face of the cam by an expandable spring L. This spring is located within a housing M, on the transmitter, and 110

it bears against a seat N, on the connector below the pivot k. The spring L, tends to turn the transmitter on the pivot k, and to maintain the cam roll l, against the cam.

5 Figs. 1 and 2 of the drawings indicate a crank arm O, fast on the shaft and a rod P, which constitute part of the mechanism of said Merrill patent whereby the rocking of the shaft A imparts movement to the reed 10 there being in practice one such arm and rod at each end of the shaft, as shown in said patent. The rod P, is urged upwardly by a spring to hold the reed in beating-up position, as set forth in said Merrill patent.

15 When the crank arm D, and connector E, are connected by the latch G, the cam B, depresses the transmitter F, and the open end or heel m, of the housing bears against the seat N, of the connector, so that the connector moves downwardly with the transmitter under the action of the cam. Since the shaft A, is then latched to the connector, it rocks and the crank arm O, and rod P, move downwardly thus swinging the reed 25 backwardly on the lay so that the weft is not forced up to the fell of the cloth. When the low part of the cam approaches the cam roll, the transmitter F, swings upwardly on its pivot k, under the push of the spring L, and rod P, arm O, arm D, and connector E, are lifted by the springs which close the 30 reed so that the strands of weft which have been laid are beaten up carrying with them the terry warp and producing the terry 35 loops.

When at the call of the pattern mechanism, the latch G, is withdrawn from the arm D, the downward thrust of the cam B, is not communicated to the shaft A, and the 40 reed stays locked thus beating up each strand of weft as soon as laid. The cam now depresses the transmitter and connector, the latter swinging on the shaft A, without rocking it. During this downward movement of the connector, the spring K, yields and the connector and its slot J, move relatively to the arm D, and its stud I. Then, as the low part of the cam approaches the cam roll l, the transmitter F, swings upwardly on its pivot k, under the influence of the spring L, and the spring K, lifts the connector E, until the bottom of the slot J, seats against the stud I. This brings the slot g and notch h into register. The timing 55 of the pattern mechanism is such that the slot g and notch h, are thus in register when the latch G is released, so that it locks the connector to the beat-up motion shaft with promptness and certainty so that full 60 length terry loops are produced when the terry weave is resumed.

During the plain weave the arm O, rises and falls as the lay swings with a corresponding movement of the arm D, and connector E. This does not, however, affect the

coöperation between the cam and cam roll since it is compensated for by the swing of the transmitter on its pivot k. Likewise, this rise and fall of the arm D, does not affect the timely registration between the locking slot g, and notch h, because the relation between the slot J, and stud I, and the action of the spring K, are independent of the position of the arm D.

During the terry weave, the connector 75 (being then locked to the arm D) is also influenced by the swing of the lay, but without affecting the action of the cam on the cam roll because of the compensating movement of the transmitter on its knuckle joint. 80

I claim—

1. A terry loom having, in combination, a 85 rocking beat-up motion shaft; a crank arm fast thereon having a laterally projecting arm; a connector loose on said shaft having a motion limiting slot through which said stud extends and a locking slot which registers with said notch when the bottom of said motion limiting slot seats against said stud; a contractile lifting spring connecting said upstanding arm and connector and acting to lift said connector; a spring actuated pattern controlled latch on said connector adapted to enter said notch and lock 90 said crank arm to the connector; a rotary open faced cam; a transmitter having a cam roll bearing against said cam; a knuckle joint connection between said connector and transmitter acting to maintain the cam roll 95 against the cam.

2. A terry loom having, in combination, a 100 rocking beat-up motion shaft; a crank arm fast thereon having a laterally projecting stud, and a locking notch; a connector loose on said shaft having a motion limiting slot through which said stud extends and a locking slot which registers with said notch when the bottom of said motion limiting slot seats against said stud; a contractile lifting 105 spring connecting said crank arm and connector and acting to lift said connector; a spring actuated pattern controlled latch on said connector adapted to enter said notch and lock 110 said crank arm to the connector; a rotary open faced cam; a knuckle joint connection between said transmitter and connector; and a spring between said connector and transmitter acting to maintain the 115 transmitter against the cam.

3. A terry loom having, in combination, a 120 rocking beat-up motion shaft; a crank arm fast thereon having a laterally projecting stud, and a locking notch; a connector loose on said shaft having a motion limiting slot through which said stud extends and a locking slot which registers with said 125 notch when the bottom of said motion limiting slot seats against said stud; a contractile lifting spring connecting said crank 130

arm and connector and acting to lift said connector; a pattern controlled latch adapted to enter said locking slot and notch and lock said crank arm to the connector; a rotary open faced cam; a transmitter bearing against said cam; a knuckle joint connection between said transmitter and connector; and a spring between said connector and transmitter acting to maintain the transmitter against the cam.

4. A terry loom having, in combination, a rocking beat-up motion shaft; a crank arm fast thereon having a laterally projecting stud; a connector loose on said shaft having a motion limiting slot through which said stud extends; a lifting spring connecting said crank arm and connector and acting to lift said connector; a pattern controlled latch adapted to lock said crank arm to the connector; a rotary open faced cam; a transmitter bearing against said cam; a knuckle joint connection between said transmitter and connector; and a spring between said connector and transmitter acting to maintain the transmitter against the cam.

5. A terry loom having, in combination, a rocking beat-up motion shaft; a crank arm fast thereon having a projecting stud; a connector loose on said shaft having a motion limiting slot through which said stud extends; a spring connecting said crank arm and connector; a pattern controlled latch adapted to lock said crank arm to the con-

necter; a rotary open faced cam; a transmitter bearing against said cam; a knuckle joint connection between said transmitter and connector; and a spring between said connector and transmitter acting to maintain the transmitter against the cam.

6. A terry loom having, in combination, 40 a rocking beat-up motion shaft; a crank arm fast thereon; a connector loose on said shaft; motion limiting means which limits the relative movement between said crank arm and connector; a spring connecting said 45 crank arm and connector; a pattern controlled latch adapted to lock said crank arm to the connector; a rotary cam; a transmitter coöperating with said cam; and a knuckle joint connection between said transmitter and connector.

7. A terry loom having, in combination, a rocking beat-up motion shaft; a crank arm fast thereon; a connector loose on said shaft; a pattern controlled latch adapted 55 to lock said crank arm to the connector; a rotary open faced cam; a transmitter having a cam roll bearing against said cam; a knuckle joint connection between said transmitter and connector; and a spring between 60 said connector and transmitter acting to maintain the cam roll against the cam.

In witness whereof I have hereunto signed my name.

ALONZO E. RHOADES.
